UNITED STATES PATENT OFFICE.

THEODORE E. REYNOLDS AND HERBERT W. MERRILL, OF SAGINAW,
MICHIGAN.

PRESSED-METAL PUMP.

No. 799,671.

Specification of Letters Patent.

Patented Sept. 19, 1905.

Application filed February 28, 1905. Serial No. 247,798.

To all whom it may concern:

Be it known that we, THEODORE E. REYNOLDS and HERBERT W. MERRILL, citizens of the United States, residing at Saginaw, in the county of Saginaw and State of Michigan, have invented certain new and useful Improvements in Pressed-Metal Pumps; and we do hereby declare the following to be a full, clear, and exact description of the invention, such as will enable others skilled in the art to which it appertains to make and use the same.

Our invention relates to improvements in hand-pumps for house service, the objects being to produce a pump that is light and of such construction that the pump body and base may be made of sheet metal and yet preserve the strength and rigidity of an ordinary cast-metal pump.

With these objects in view our invention consists in certain novel features of construction and their equivalents described in the specification and set forth in the claims.

In the accompanying drawings, Figure 1 is a perspective showing the pump complete. Fig. 2 is a part vertical section through the center of the pump. Fig. 3 is a perspective view of the barrel, the funnel-shaped chamber, and the spout. Fig. 4 is a view of the cover. Figs. 5 and 6 are views of the gasket-plate which is secured between the barrel and the base. Fig. 7 is a perspective view of the base. Figs. 8 and 9 are views of the pressed-metal pump-handle. Fig. 10 shows the funnel-shaped chamber developed. Fig. 11 shows the development of the spout. Fig. 12 shows the development of the base.

A is the base, made of a single piece of sheet metal stamped out, as shown in Fig. 12, and pressed to the form shown in Fig. 7. It has three downwardly-projecting legs a, formed integral with the flat top a'. Each leg has a beaded rib a'', which gives it the necessary stiffness. The flat top a' has a central opening a''', through which passes the suction-pipe.

B is a gasket-plate resting upon the base A and forming a tight joint between the base A and the flange d' of the barrel D. The gasket-plate has a central opening b', registering with the opening a''' of the base A. The half-nipple b'' has a shoulder b''' turned on it, the projecting end of which extends up through the opening b' in the plate and is beaded over on the upper side, thus making a tight joint. The suction-pipe C can be connected to the

nipple b'' by a coupling e or other suitable means.

The barrel D comprises a sheet-metal cylindrical portion having a flanged base d', which is securely fastened to the base A by means of the bolts d''. The top of the barrel is flanged out, as shown at d''', to fit the funnel-shaped chamber E and is either beaded, brazed, or soldered to it.

The sheet-metal chamber E is shaped like an inverted truncated cone. Its upper edge e is flanged in and forms an annular supporting-ring, to which the cover G is bolted. An opening e' in the side of the chamber communicates with the spout F. The spout F is of sheet metal and is of the ordinary shape. It is secured to the wall of the chamber E by brazing, soldering, or otherwise.

The chamber E is closed by the cover G, fastened by bolts g' passing through the flange e. The cover is dished and its edges are flanged down around the outside edge of the chamber E to make a tight joint and prevent the cover being displaced. The cover has a slotted hole g to receive the plunger-rod R, and it also has two lugs or brackets g'', which support the handle H. These lugs are secured to the cover by rivets g''' or otherwise.

The handle H is of the general shape shown in Figs. 8 and 9 and is formed of two pressed-metal members fastened together by rivets h, as shown.

The plunger I and the foot-valve K are the same as in an ordinary cast-metal pump.

This novel construction produces a pump that is much less expensive to manufacture than the ordinary cast pump of the same capacity. It can be readily taken apart for cleaning or repairing and is not liable to get out of order. In shipping long distances by freight its lightness enables its selling and distributing area to be increased much beyond that of the common cast pumps. Breakage in shipment or in use is almost entirely eliminated, and any part of the pump bent in shipment can be easily straightened without the use of special tools.

What we claim as our invention, and desire to secure by Letters Patent, is as follows:

1. A cistern-pump comprising a base formed of a single piece of sheet metal; a gasket-plate resting upon the base, said gasket-plate having a central opening; a downwardly-projecting nipple in said opening; a foot-valve

- carried by said plate; a barrel comprising a sheet-metal cylindrical portion having a flanged base and having an outwardly-flaring upper portion formed of sheet metal, the upper edge of said flaring portion being flanged inwardly to form an annular supporting-ring; a spout secured to said upper portion; a cover formed of sheet metal and having its edges flanged downwardly; sheet-metal lugs secured to said cover and a handle formed of sheet metal pivotally mounted in said lugs; together with a plunger connected to said handle, substantially as described. 25
2. A shell for cistern-pumps comprising a base formed of sheet metal; a gasket-plate having a downwardly-projecting-nipple; a cylindrical body formed of sheet metal and having its lower end provided with a flange; a funnel-shaped chamber formed of sheet metal and secured to the upper end of said cylindrical body; a sheet-metal spout secured to said 30
- chamber; a flanged cover for said chamber formed of sheet metal; lugs secured to said cover and a handle pivotally mounted on said lugs, substantially as set forth. 35
3. A shell for cistern-pumps comprising a base formed of sheet metal; a gasket-plate having a downwardly-projecting nipple; a cylindrical body formed of sheet metal and having its lower end flanged outwardly; a sheet-metal spout secured to said chamber; a flanged cover for said chamber formed of sheet metal; lugs secured to said cover and a handle pivotally mounted on said lugs, substantially as set forth. 30

In testimony whereof we affix our signatures in presence of two witnesses.

THEODORE E. REYNOLDS.
HERBERT W. MERRILL.
